(57) **CLAIM**

The ornamental design for a lint remover, as shown and described.

DESCRIPTION

FIG. 1 is a front elevational view of a lint remover showing my new design;

FIG. 2 is a rear elevational view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof, taken from the front and right side;

FIG. 8 is a perspective view thereof, taken from the rear and right side;

FIG. 9 is an enlarged perspective view thereof, taken from below; and,

FIG. 10 is an enlarged view of portion 10 shown in FIG. 8. The broken-line circle shown in broken lines in FIGS. 8 and 10 illustrate the bounds of the portion of FIG. 8 that is shown in the enlargement in FIG. 10 and form no part of the claimed design. The remaining broken lines depict portions of the lint remover that form no part of the claimed design.

1 Claim, 9 Drawing Sheets
